UNITED STATES PATENT OFFICE.

CYRUS S. HINDERLITER, OF EDDYVILLE, PENNSYLVANIA.

HOOK.

Application filed August 16, 1922. Serial No. 582,230.

To all whom it may concern:

Be it known that CYRUS S. HINDERLITER, a citizen of the United States, residing at Eddyville, in the county of Armstrong and

5 State of Pennsylvania, has invented certain new and useful Improvements in Hooks, of which the following is a specification, reference being had to the accompanying drawings.

10 This invention relates to certain improvements in hooks and has relation more particularly to a device of this general character especially designed and adapted for use in connection with curtain rods and it 15 is an object of the invention to provide a device of this general character comprising novel and improved means whereby the same may be shortened or lengthened as the occasions of practice may require.

20 Another object of the invention is to provide a novel and improved device of this general character comprising telescopically engaged members and wherein said members are provided with co-acting means for holding the same in desired relative adjustments.

25 The invention consists in the details of construction and in the combination and arrangement of the several parts of my improved hook whereby certain important advantages are attained and the device rendered simpler, less expensive and otherwise more convenient and advantageous for use, as will be hereinafter more fully set forth.

30 The novel features of my invention will 35 hereinafter be definitely claimed.

In order that my invention may be the better understood, I will now proceed to describe the same with reference to the accompanying drawings, wherein:

40 Figure 1 is a view in perspective illustrating a hook constructed in accordance with an embodiment of my invention and in applied position.

Figure 2 is a view partly in section and 45 partly in elevation of the device; and

Figure 3 is an enlarged sectional view taken substantially on the line 3—3 of Figure 2.

50 As disclosed in the accompanying drawings, 1 denotes a plate of requisite dimensions which is adapted to be secured to a window facing or other support as may be preferred.

55 Extending outwardly from the plate 1 and at substantially the central portion thereof is an elongated tubular arm 2 provided in

the under portion of its wall with a series of longitudinally spaced openings 3.

Telescopically engaged within the member 2 is an elongated shank 4 having its outer end angularly disposed to provide an upstanding bill or hook 5 for co-action in a well known manner with a curtain or the like. The inserted end portion of the shank 4 is extended to provide a spring member 6 continued by returned spring portions 7, the portion 7 being of such configuration to have its extremity contacting with the upper portion of the wall of the member 2.

The spring 6 has depending therefrom a button 8 which is adapted to extend through an opening or slot 3 whereby the shank 4 may be held in different adjusted positions with respect to the member 2.

When it is desired to adjust the shank 4 with respect to the member 2 it is only necessary to push the button 8 inwardly sufficient to free the same from locking engagement with the member 2 whereupon the requisite endwise movement may be readily imparted to the shank 4.

My improved device is particularly adapted for use when hanging curtain rods where the window facing is not of sufficient width. With the use of my device instead of blocking out even with the facing the hook may be attached to the wall and the shank 4 adjusted with respect to the member 2 to position the bill or hook 5 as desired.

From the foregoing description it is thought to be obvious that a hook constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. Fastening means for an adjustable curtain rod comprising a tubular member having openings disposed at spaced intervals longitudinally thereof, a rod adapted to snugly fit the tubular member, one end of said rod being flattened to provide a resilient strip, the end portions of said strip being

extended back upon the strip to provide a substantially U-shaped spring member, the distance between said members being slightly less than the diameter of the rod, and a snap button projecting from said strip adjacent the junction of said strip with the rod, the reverted end portion of the strip being adapted to engage the inner surface of the tubular member remote from the opening and coacting with the snap button to prevent movement of the rod relative to the tubular member.

2. An adjustable curtain rod support comprising a tubular member adapted to have one end secured to a support and having a longitudinal series of spaced openings, a curtain rod supporting shank having one end portion slidable in the tubular member, the inner end of said end portion of the shank being flattened and extended backwardly upon itself to provide a spring member having spaced portions engaging the inner faces of opposed portions of said tubular member, and a lug carried by the spring member and normally urged into an opening of the tubular member through the medium of the resiliency of the spring member.

3. An adjustable supporting device including an arm having means to attach one end thereof to a support, and an article supporting shank having its inner end slidably positioned for longitudinal movement in said arm and having its outer end free and formed to engage the article to be supported, said shank having its inner end flattened and extended backwardly upon itself to provide a spring member embodying spaced portions engaging the inner faces of opposed portions of said arm to retain the arm and shank against accidental relative longitudinal displacement.

4. An adjustable supporting device including an arm having means to attach one end thereof to a support, and an article supporting shank having its inner end slidably positioned for longitudinal movement in said arm and having its outer end free and formed to engage the article to be supported, said shank having its inner end flattened and extended backwardly upon itself to provide a spring member embodying spaced portions engaging the inner faces of opposed portions of said arm to retain the arm and shank against accidental relative longitudinal displacement, the formation of the outer end of said shank providing an upstanding bill or hook adapted to engage the end openings of a conventional adjustable curtain rod.

5. An adjustable supporting device including an arm having means to attach one end thereof to a support, and an article supporting shank having its inner end slidably positioned for longitudinal movement in said arm and having its outer end free and formed to engage the article to be supported, said shank having its inner end flattened and extended backwardly upon itself to provide a spring member embodying spaced portions engaging the inner faces of opposed portions of said arm to retain the arm and shank against accidental relative longitudinal displacement, said arm having a longitudinal series of spaced openings, and a lug carried by a portion of said spring member normally yieldingly urged into one of said openings and manually releasable therefrom against the action of said spring member.

In testimony whereof I hereunto affix my signature.

CYRUS S. HINDERLITER.
